UNITED STATES PATENT OFFICE.

JAMES C. GROSS, OF SCRANTON, PENNSYLVANIA.

STOPPING AND SIGNALING MECHANISM FOR LOCOMOTIVES.

SPECIFICATION forming part of Letters Patent No. 446,288, dated February 10, 1891.

Application filed September 9, 1890. Serial No. 364,430. (No model.)

To all whom it may concern:

Be it known that I, JAMES C. GROSS, of Scranton, in the county of Lackawanna and State of Pennsylvania, have invented a new and Improved Stopping and Signaling Mechanism for Locomotives, of which the following is a full, clear, and exact description.

The object of the invention is to provide a new and improved stopping and signaling mechanism for locomotives, which is simple and durable in construction and intended for automatically stopping the locomotive and sounding the whistle at or near the stations or other predetermined places, at the same time permitting the engineer to apply or release the brakes, work the throttle-valve, or sound the whistle at any time and place he desires.

The invention consists of certain parts and details and combinations of the same, as will be hereinafter fully described, and then pointed out in the claims.

Reference is to be had to the accompanying drawings, forming a part of this specification, in which similar letters of reference indicate corresponding parts in both the figures.

Figure 1 is a sectional side elevation of the improvement, and Fig. 2 is a plan view of part of the improvement for operating the engineer's valve.

The improved stopping and signaling mechanism is provided with a cylinder A, secured on the tender or locomotive and containing the piston B, pressed in a lower or normal position by a spring C, arranged within the cylinder, as is plainly shown in Fig. 1. The piston B is provided with a downwardly-extending piston-rod D, adapted to be engaged by a socket E', formed on the upper end of a rod E, fitted to slide in suitable bearings formed on the frame carrying the cylinder A. On the lower end of the rod E is journaled a roller E², adapted to pass over an auxiliary rail F, located at or near the main rail at a predetermined place—that is, near a station, switch, &c.—so that the locomotive when reaching said predetermined place causes the roller E² to pass up the inclined rail F to move the rod E upward. At this upward movement the socket E', pressing against the piston-rod D raises the piston B from its

seat in the lower part of the cylinder A. When the friction-roller E² has passed over the incline of the rail F, then a spring E³, pressing against the rod E, holds the roller E² in a normal lower position.

Into the lower end of the cylinder A leads one end of a pipe G, connected with a reservoir containing a fluid under pressure, the end of the pipe G, leading into the cylinder A, being normally closed by the piston B. When the latter is raised, as previously described, by the action of the track-rail F on the roller E², then the piston B uncovers the opening of the pipe G and the fluid under pressure can pass into the said cylinder A. From the cylinder A leads an outlet-pipe H, arranged opposite the pipe G and provided with a check-valve H' and leading into a small reservoir I, from which lead a number of pipes J, J', J², and J³, of which the latter is provided with a valve and serves as an outlet or escape. The pipe J leads into a cylinder K, containing a piston K', provided with a piston-rod K', pivotally connected by a movable pin K³ with a slotted link L, loosely connected with an arm L', adapted to be fulcrumed on the valve-stem N' of the engineer's valve N, of any approved construction, and provided with the usual valve-stem handle N², which is taken hold of by the engineer to operate the engineer's valve in the usual manner. The pivotal connection between the arm L' and the link L is such that the engineer can at any time work the engineer's valve N by manipulating the handle N² without interfering with the position of the piston K' in the cylinder K. When, however, the fluid under pressure passes into the cylinder K from the pipe J, then the piston K' moves outward and by its piston-rod K², the link L, and the arm L' turns the stem of the engineer's valve, so as to apply the brakes. When the engineer does not desire the brakes to be applied automatically, he removes the pin K³, so as to disengage the piston-rod K² entirely from the engineer's valve. The pipe J' leads into a cylinder O, containing a piston O', provided with a piston-rod O², connected at its outer end by a pin O³ with a lever P, connected with the throttle-valve of the locomotive. When the piston O' is moved out-

ward by a fluid passing through the pipe J' into the cylinder O and pressing against the said piston, then the lever P is actuated and shuts the throttle-valve, so that the motive agent for the engine is shut off. The pipe J^2 connects with a cylinder Q , containing a piston Q' , provided with a piston-rod Q^2 , pivotally connected with a link Q^3 , having a slotted end engaging a stud on the bell-crank lever R , connected by one arm with the rod R' , operating the whistle, and connected by its other arm with a rod y under the control of the engineer for sounding the whistle whenever he desires. The branch pipe G^2 leads from the pipe G directly to the reservoir I , the said pipe being provided with a valve G^3 , as is plainly shown in Fig. 1.

The operation is as follows: When the engine nears a station, a curve, switch, or other place at which an auxiliary rail F is located, the roller E^2 in traveling up the rail F moves the piston B upward, so that the fluid under pressure from the pipe G passes into the cylinder A , and from the latter through the pipe H past the check-valve H' into the reservoir I . From here the fluid under pressure actuates the engineer's valve N , as previously described, so that the brake mechanism is applied, and at the same time the fluid under pressure from the reservoir I passes into the cylinder O to close the throttle-valve, as previously mentioned, and the fluid under pressure passes up the pipe J^2 and actuates the piston Q' , so as to swing the bell-crank lever R , thereby sounding the whistle. It will be seen that thus a signal is given, the steam is shut off from the engine, and the brake mechanism is applied, so that the locomotive or train must come to a dead stop in a short time. When the engineer desires to signal, to shut off the throttle-valve, and to apply the brakes without using the cylinder A , its piston B , the roller E^2 , and the rail F , then he closes the valve G' and opens the valve G^2 , so that the fluid under pressure can pass directly from the pipe G to the reservoir I , and from there to the several cylinders K , O , and Q , to actuate the brake mechanism, the throttle-valve, and whistle, as previously described. When the engineer desires to reset the apparatus, he opens the pipe J^3 to let the air escape from the reservoir I . It will be seen that the device does not interfere with the engineer's operating the brake mechanism, the throttle-valve, or the whistle, each independently of the other, and of the automatic device described.

Having thus fully described my invention, I claim as new and desire to secure by Letters Patent—

1. The combination, with the cylinder A , having inlet and outlet pipes G , H at its lower end, a piston B , closing the adjacent ends of said pipes and provided with a piston-rod D , extending down through the lower end of the cylinder, and the spring C in the cylinder and holding the piston down, of the rod E below

and in vertical alignment with the rod D , a cup-like socket on the upper end of rod E receiving the lower end of rod D , but disconnected therefrom, and a spring E^3 , pressing rod E downward, the lower end of the rod E being adapted to be operated by a track projection, substantially as set forth. 70

2. A stopping and signaling mechanism comprising a cylinder having an inlet connected with a fluid-supply, and also provided with an outlet, and a reservoir connected with the said outlet and having a series of pipes connected with mechanism for actuating the engineer's brake-valve, the throttle-valve, and the whistle, and a piston held in the said cylinder and adapted to open and close the said inlet and outlet, substantially as shown and described. 75

3. A stopping and signaling mechanism comprising a cylinder having an inlet connected with a fluid-supply, and also provided with an outlet, and a reservoir connected with the said outlet and having a series of pipes connected with mechanism for actuating the engineer's brake-valve, the throttle-valve, and the whistle, a piston held in the said cylinder and adapted to open and close the said inlet and outlet, and an auxiliary rail for actuating the said piston, substantially as shown and described. 80 90

4. In a stopping and signaling mechanism, the combination, with a cylinder provided with an inlet and connected with a fluid-supply, and also provided with an outlet, of a spring-pressed piston held in the said cylinder and controlling the said inlet and outlet, an auxiliary rail for actuating the said piston to connect the said inlet with the outlet, a fluid-reservoir into which opens the said outlet, and a cylinder connected with the said reservoir and containing a piston connected with the engineer's brake-valve, substantially as shown and described. 100 105 110

5. In a mechanism of the character described, the combination, with a cylinder provided with an inlet and outlet for the motive fluid, and a spring-seated piston in said cylinder closing said openings and having a piston operated from a track projection, of a second cylinder connected with the outlet of the first-named cylinder, and having a piston provided with a rod and a slotted operating-link to form a loose connection between said rod and the part which it is to operate to permit said part to be also operated independently of said second piston, substantially as set forth. 115 120 125

6. The combination, with a cylinder having an inlet and outlet and a piston or valve operated by a track projection and controlling said inlet and outlet, and a second cylinder having a fluid-operated piston connected with the part to be operated, of a pipe H , connecting said cylinders and having a check-valve H' , a fluid-supply pipe G , leading to the first-named cylinder and provided with a valve G' , and the pipe G^2 connecting pipe G with pipe H' above its check-valve, whereby by closing 130

valve G' and opening valve G³ the fluid may pass directly to the second cylinder to operate its piston, substantially as set forth.

7. In a stopping mechanism, the combination, with a cylinder connected with a fluid-supply, of a piston operating in the said cylinder, a piston-rod connected with the said piston, a slotted link connected by a removable pin with the said piston-rod, and an arm

adapted to be clamped onto the stem of the engineer's valve and pivotally connected with the said link, substantially as shown and described.
